(57) **CLAIM**

I claim the ornamental design for pump components, as
shown and described.

DESCRIPTION

FIG. 1 is a first perspective view of pump components in
accordance with an embodiment of my new design illustrating
a pump;

FIG. 2 is a second perspective view of the pump components of
FIG. 1;

FIG. 3 is a rear elevation view of the pump components of
FIGS. 1-2;

FIG. 4 is a front elevation view of the pump components of
FIGS. 1-3;

FIG. 5 is a right side elevation view of the pump components of
FIGS. 1-4;

FIG. 6 is a left side elevation view of the pump components of
FIGS. 1-5;

FIG. 7 is a top view of the pump components of FIGS. 1-6;
and,

FIG. 8 is a bottom view of the pump components of FIGS.
1-7.

The portions of the pump components shown in broken lines
in the figures depict unclaimed environmental subject matter,
are for illustrative purposes only, and form no part of the
claimed design.
